(57) CLAIM

I claim the ornamental design for sports bra with center storage pocket, as shown and described.

DESCRIPTION

FIG. 1 is a front top perspective view of a sports bra with center storage pocket showing my new design;

FIG. 2 is a front elevation view thereof;

FIG. 3 is a rear elevation view thereof;

FIG. 4 is a side elevation view thereof;

FIG. 5 is a top plan view thereof; and,

FIG. 6 is a bottom plan view thereof.

The broken lines shown in the drawings are stitching and form a part of the claimed design.
